HAND BRUSH

Rudolf Vogel, 1140 Laurel Ave.,
Bridgeport, Conn. 06604

Filed Feb. 6, 1970, Ser. No. 21,305

Term of patent 14 years

Int. Cl. D4—02; D28—03

U.S. Cl. D4—13

FIG. 1

FIG. 2

FIG. 3

FIG. 4

FIG. 5

FIG. 1 is a perspective view of a hand brush, showing my new design;

FIG. 2 is a top plan view;

FIG. 3 is a side elevational view of one side, the opposite side being identical;

FIG. 4 is an end elevational view of one end, the opposite end being identical; and,

FIG. 5 is a bottom plan view with a portion omitted for ease of illustration.

I claim:

The ornamental design for a hand brush, substantially as shown and described.
